UNITED STATES PATENT OFFICE.

HUGH L. WARNER, OF DAYTON, OHIO.

DESIGN FOR A RUNNING-GEAR FOR MOTOR-VEHICLES.

SPECIFICATION forming part of Design No. 34,632, dated June 4, 1901.

Application filed May 3, 1901. Serial No. 58,666. Term of patent 14 years.

To all whom it may concern:

Be it known that I, HUGH L. WARNER, a citizen of the United States, residing at Dayton, in the county of Montgomery and State of Ohio, have invented and produced a new and original Design for a Running-Gear for a Motor-Vehicle; and I do declare the following to be a full, clear, and exact description of the same, reference being had to the accompanying drawing, forming a part thereof.

The drawing is a perspective view of a running-gear, showing my new design.

As shown in the drawing, the leading or material feature of my design consists of rear and front frames, each of which is composed of two parallel bars A A' B B', which are joined by two reaches C C'.

D D' E E' designate braces connecting the reaches to the outer ends of said rear and front frames.

F F' are lugs or frame connections which have socket-lugs F'' F'', that receive the outer ends of the parallel bars B B', constituting the rear frame of the running-gear. The said 25 lugs F F' also have socket ends G G'.

H H' are lugs or frame connections which have socket-lugs H'' H'', that receive the ends of the parallel bars A A', constituting the front frame of the running-gear.

I I' are pivot-axles mounted in said lugs 30 H H'.

J is a gear-case having socket-lugs K K' L L', by means of which it is connected to the parallel bars B B', constituting the rear frame of the running-gear.

M designates standards forming connections between the front and rear frames and the reaches C C'.

Having described my invention, what I claim as new, and desire to secure by Letters 40 Patent, is—

The design for a running-gear for a motor-vehicle, as herein shown and described.

In testimony whereof I affix my signature in presence of two witnesses.

HUGH L. WARNER.
